COMBUSTION CONTROL

Henry J. Keeley, Denver, Colo.

Application January 2, 1934, Serial No. 705,035

14 Claims. (Cl. 236—15)

This invention relates to an electrical control system for fuel burners, and while it is more particularly designed for use with the burner disclosed in applicant's copending applications, Serial No. 691,649, filed Sept. 30, 1933, and Serial No. 5 697,637, filed Nov. 11, 1933, it is of course not limited to use in connection with these particular installations.

The principal object of this invention is to 10 provide a control system for fuel burner which will not only provide any desired preset temperature to the medium being heated, but will maintain this temperature with the greatest possible efficiency of fuel consumption.

Another object of the invention is to provide a 15 simple highly efficient electrical system which will control the amount of fuel being fed to a burner automatically in accordance with a relation between the temperature of the burner and the temperature of the cold outside air or other medium which it is desired to heat.

A further object is to provide a control circuit 20 which will automatically control the amount of air being fed to a burner to obtain the most efficient relation between flue gas temperature and the carbon dioxide content of the flue gases, and so as to obtain a neutral flame at all times.

A still further object is to provide means for 25 shutting down the entire plant should the fire fail to ignite or should the flame die out.

Thermostats have been heretofore applied to 30 control the fuel feed of a heating plant burner in accordance with inside or room temperature without regard to outside temperatures. The present invention, however, controls the fuel feed according to a relation between the burner and the outside temperatures, thus should the 35 outside temperature fall the fire will be automatically increased without requiring a consequent lowering in the inside temperatures and vice versa.

The present invention also controls the air to 40 the burner in accordance with the chemical requirements of the burning fuel and not in accordance with the amount thereof as in present 45 installations. The control of air to a burner in consequence of flue gas temperature alone is not completely efficient operation since it does not take into consideration the carbon dioxide percentage in the fuel gases. The present invention 50 controls the air automatically according to the requisite scientific relation between the flue gas temperature and the carbon dioxide percentage to obtain complete combustion without excess air at all times.

Other objects and advantages reside in the detail construction of the invention, which is designed for simplicity, economy, and efficiency. These will become more apparent from the following description.

In the following detailed description of the invention reference is had to the accompanying drawings which form a part hereof. Like numerals refer to like parts in all views of the drawings and throughout the description.

In the drawings:

Fig. 1 is a plan view of a portion of the control mechanism of a typical burner to which the present control system is applicable.

Fig. 2 is a circuit diagram of the portion of 15 the control system controlling the fuel feed to the burner.

Fig. 3 is a circuit diagram illustrating the control system for the air feed to the burner.

Fig. 4 is a circuit diagram illustrating a circuit 20 for controlling the main current supply in accordance with a relation between the outside temperature and the steam pressure.

The burner feed mechanism of Fig. 1 is described and illustrated more in detail in applicant's copending application, Serial No. 691,649, 25 filed Sept. 30, 1933, and will but be briefly outlined here, to illustrate a typical feed mechanism to which the present invention may be applied. Briefly, it consists of a driving motor 10 operating a cam 11 through the medium of a suitable 30 reduction gear 12. The cam 11 reciprocates a ratchet member 13 which in turn drives a fuel feed conveyor 14 through the medium of a ratchet gear 15 through suitable transmission gears 16. The ratchet member 13 can be made to engage 35 more or less teeth of the ratchet gear 15 by movement of a wedge member 17. The wedge member is moved into greater or less engagement by means of a fuel feed control motor 18.

The air for the burner is furnished from a blower 19, the intake of which, is controlled by a means of an arcuate rack 20 operated from an air control motor 21. The rack 20 and the wedge member 17 are simply illustrative of one of mechanical expedients for controlling the air and fuel 45 supply. The motors 21 and 18 could be connected with any other desired mechanism which would control the air and fuel supply. The controls are preferably operated from low voltage direct current furnished by a D. C. generator 22 driven by 50 the motor 10, which in the usual installation would be an A. C. Motor.

In controlling the motor 18 a compact thermo-responsive device 23 is employed, as indicated diagrammatically in Fig. 2. This device con- 55

sists of two electrically controlled temperature gauge mechanisms, one of which actuates a hand 24 which may be the indicating hand of any standard electrically operated temperature gauge. 5 The other mechanism similarly and independently controls an independent hand 25. The gauge mechanism for operating the hand 24 is connected through a pair of conductors 26 with a suitable thermo-couple positioned on the exterior of the 10 building in which the heating plant is located so as to cause the hand 24 to move in consequence of the changes in exterior temperature. The mechanism for operating the hand 25 is connected by means of a pair of conductors 27 with 15 a thermo-couple positioned in the firebox or bowl of the heater. The interior construction of the gauge 23 forms no part of the present invention, and may be any of the commercial thermogauges, the indicating hands of which could be 20 used for the hands 24 and 25. For convenience, it will be assumed that the exterior temperature hand 24 moves to the "right", Fig. 2, to indicate falling temperature and that the burner temperature hand 25 moves to the "left" to indicate 25 a falling temperature.

The hands 24 and 25 are each provided with an electrical contact 28 and 29, respectively, which are connected through conductors 30 with a polarized relay 31. The polarized relay 31 consists of a first electro-magnet 32 and a second electro-magnet 33 which alternately act upon an armature 34 to alternately close a contact 35 and a contact 36. The contacts 35 and 36 control the direction of rotation of the armature of the fuel 35 feed control motor 18 which is connected by means of suitable conductors 37 with the generator 22. The electro-magnet 33 is always in circuit, through a resistance 38, with the generator 22 so that it will always be pulling the armature 40 34 toward the contact 36. The electro-magnet 32 is in circuit with the thermo-gauge contacts 28 and 29 through a relatively smaller resistance 39.

Let us assume that the outside temperature is 45 comparatively low so that the hand 24 is toward the right or low temperature position of Fig. 2 and that the fire has been started in the burner. The operation of the generator 22 will energize the magnet 33 so as to close the contact 36 and 50 cause the motor 18 to operate the wedge member 17, forwardly to increasingly feed fuel to the burner. Now let us assume that the fire raises the fire box temperature to cause the hand 25 to swing toward the right. Eventually a position 55 will be reached when the contacts 28 and 29 will close, thus closing the circuit to the magnet 32. The latter magnet will have a greater pull than the magnet 33, owing to the differences in the resistance 38 and 39, so as to cause the armature 60 34 to close the contact 35. This reverses the motor 18 and causes it to gradually withdraw the wedge member 17 and thus gradually reduce the amount of fuel by a feed to the burner. This will continue until the fire temperature begins 65 again to fall so as to separate the hand 25 from the hand 24 and allow the fuel feed motor 18 to resume its forward direction.

Of course, as the combustion increases, the supply of air must also be increased. This is accomplished by the circuits shown in Fig. 3 in 70 which a thermo-gauge 49 having a thermometer hand 41 is employed. The thermo-gauge 40 is connected through suitable conductors 42 with a thermo couple in the stack outlet of the heater 75 and as the stack temperature rises, the hand 41

will swing to the right and as it lowers it will swing to the left. A pivoted rack lever 44, operated from a rack 45 and a worm 46, is incorporated in the thermo-gauge 40. The rack lever is provided with a contact 43 and the hand 41 5 is provided with a coating contact 54. The worm 46 is driven from a small motor 47, the control of which will be later described.

The thermo-gauge 40 is for controlling the operation of the air feed motor 21 which is connected through suitable conductors 48 with the generator 22. The control is effected through a second polarized relay 49 similar to the previously described relay 31 and consisting of a first and second electromagnet 50 and 51, respectively, and an armature 52 swinging between motor reversing contacts 53. Normally the armature is drawn toward the magnet 51 to cause the motor 21 to rotate, forwardly, in a direction which will gradually open the air intake of the blower 19. When 20 the flue gas temperature reaches a predetermined optimum point the contact 54 on the thermo-responsive hand 41 will close the contact 43, thereby energizing the magnet 50 and causing the armature 52 to reverse the direction of the 25 motor 21 so as to gradually close the air intake to the blower 19.

The optimum point for reversing the motor 21 is a variable which cannot be efficiently preset in advance. The flue gas temperature may be 30 affected by many things, such as the use of pre-heaters which would have a cooling effect on the flue gases and would lower the optimum point in the gauge 40; unevenness in the fuel bed, blow holes, etc., would also effect the flue gas temperature by the passage of heat due to excess oxygen; variations in the fuel etc., would also affect it. All of these things would cause a movement in the hand 41 yet would not necessarily indicate the condition of combustion. Therefore, means are provided for moving the contact 43 in consequence of the actual CO₂ percentage in the flue gases so as to always place the optimum point at the proper point for perfect combustion of the fuel then burning. This is accomplished through the medium of a CO₂ indicator 55, having a hand 56 which moves in consequence of variations in the CO₂ percentage in the stack gases. This may be any of the standard types of CO₂ indicators which operate chemically or electrically. The indicator is connected with the stack filter elements or electrodes by means of suitable conductors 72. The indicator 55 controls the direction of rotation of a small motor 47 and through it the movement of the 55 rack lever 44 so as to set the contact 43 at various points depending upon the CO₂ content of the flue gases.

The small motor 47 is directly controlled from a relay 71 which in turn is controlled through 60 conductors 73 from a pair of contacts 74 on an oil plunger relay 70. The relay 71 has left and right electromagnets 75 and 76, respectively, actuating an armature 77. The left electromagnet 75 is constantly energized through a suitable resistance and normally holds the armature 77 to the left, a position which causes the motor 47 to rotate forwardly and move the rack arm 44 to the right, away from the hand 41. Action of the relay 70 to close the contacts 74 will swing 70 the armature 77 and reverse the motor 47 to cause the rack arm to swing to the left.

The oil plunger relay 70 is operated from a pair of contacts 62 mounted on a rack arm 58 in the CO₂ indicator. These contacts are closed 75

by the contact closer 57 on the CO₂ hand 56. They are connected by means of a pair of conductors 65 to an electromagnet 68 in a relay 69. The relay 69 has a second electromagnet 78 which is constantly energized to pull an armature 79 against a contact 80. The armature 79 and contact 80 normally close the circuit to the oil plunger relay 70.

The rack arm 58 of the CO₂ indicator is actuated by a motor 60 through a rack 59 and worm 61. The motor 60 is controlled by differential, polarized, reversing relay 67, a magnet 81 of which is connected with offscale contacts 64, of the indicator 55, through conductors 82. The contacts 64 are closed by a circuit closer 63 when the rack arm swings to its extreme right position. The relay 67 is of a type to hold the relay armature 83 against the last energized magnet when the energizing current is off. When in contact with magnet 81, motor 60 will swing arm 58 to the left, and when in contact with the left magnet, will swing the rack arm 58 to the right. A second electromagnet 66 in the relay 67 swings the armature to reverse the motor 60 and move the tip of rack arm 58 to the right. The second magnet 66 is in series with the conductors 65 from the contacts 62.

The current supply to the motor 60 from the generator 10 flows through a pair of conductors 84 which lead to normally closed contacts 85 on the oil plunger relay 70 and to a pair of normally open contacts 86 on a second oil plunger relay 87.

The relay 87 is connected through a pair of conductors 88 with a pair of normally open contacts 89 on the relay 70. A pair of normally open contacts 90 on the relay 87 are bridged across the conductors 82 to the magnet 81. The relay 87 is set for a shorter time interval than the relay 70, for instance, the relay 87 may be set to operate in one minute and the relay 70 in three minutes.

As the fire increases, the flue temperature and the CO₂ content will gradually increase to bring the contact closer 57 across the contacts 62. This breaks contact at 79-80, instantly trips and opens the oil relay 70; breaks contact at 74 and allows armature 77 to start motor 47 forwardly; swings armature 83 to left and starts motor 60 forwardly. We now have a condition where both rack levers 44 and 58 are moving to the right followed by the hands 41 and 56. A point will be eventually reached when the CO₂ content will begin to diminish owing to the fact that the constant increase in the air supply will provide more air than can be used by the fuel supply. This temporarily stationary value of the CO₂ percentage will cause the hand 56 to stop and will break contact at 62. This causes armature 83 to reverse the CO₂ indicator motor 60 and the armature 79 to energize the oil relay 70. The rack arm 58 now starts toward the left and if the CO₂ content continues to fall for three minutes (or other interval to which the relay 70 is set) the relay 70 will act to close contacts 74 actuating relay armature 77 and reversing motor 47 to swing rack arm 44 to the left. The rack arm 44 will then cause contacts 43 to close and reverse the air control motor 21 to gradually close off the air supply. The actuation of relay 70 will also close contacts 89 and will open contacts 85. The latter opening will shut off the current supply to motor 60 so that the rack arm 58 will cease its leftwise movement. The closing at 89 will supply current to the oil relay 87. If the falling content be still uncorrected for an-

other minute (the interval of relay 87) the relay 87 will close contacts 86. Thus again starting motor 60 so that the contact 62 will move towards the circuit closer 57.

When contact is again made at 62 by an increase in the CO₂ content, armature 83 will reverse motor 60 and open contacts 79-80 to reset relays 76, 71, and 87; and rack levers 44 will start to the right, the air will increase, and the entire cycle will repeat.

With the tip of rack arm 58 moving slowly to the right, contact will be broken at 57-62, allowing armature 83 to rest against contact of relay magnet 66 of relay 67. This also allows armature 79 of relay 69 to assume its normal position of contact against 80 thereby energizing the circuit which operates the oil relay 70. If this condition maintains for the time interval to which relay 70 is adjusted, then the latter will operate to open circuit 85, and close circuits 73 and 88 at contacts 74 and 89. The opening of circuit 85 will stop the rotation of motor 60 by opening its power circuit thereby holding rack arm 58 stationary for the time being. Closing circuit 88 at contacts 89 will energize the solenoid of the second oil plunger relay 87. Closing of circuit 73 at contacts 74 will place armature 77 of relay 71 against the contact of magnet 76 and will reverse the direction of rotation of motor armature 47 sending the tip of rack arm 44 to the left to immediately reduce the amount of intake air. Should the circuit remain broken at 57-62 for the additional period of time to which the oil relay 87 is adjusted, then the latter will operate the switch assembly attached thereto closing circuit contacts 86 and 90. Closing contact 90 will attract armature 83 against the contact of magnet 81 of relay 67 setting the direction of rotation of the motor 60. Since the contacts 90 are closed at this time this will complete the power supply circuit to motor 60 thereby again starting the tip of rack arm 58 to the left to make contact again with 57. When they again meet they will reset all relays in preparation for another cycle of operation.

Normally however, the break of the circuit at 62 will be only momentary so that the delayed relay 70 will not operate.

It will be noted from the above that the optimum point of contact between 54 and 43 on the flue temperature gauge depends upon a complete combustion of the fuel then burning. It will be seen that the relation of quantity of fuel, proper air supply, flue gas temperature, and the CO₂ content of the flue gases is constantly controlled so that complete combustion is had at all times. Each function affects the others in such a way to maintain a maximum CO₂ content on the flue gases and a neutral flame in the fire bowl at all times.

The off scale contact 64 is provided to reverse the rack arm 58, should it accidentally reach an off scale position to the right. A second off scale contact 91 is provided on the left or zero side to be contacted by a circuit closer 92 should the rack arm reach the zero indication.

The latter condition would only occur if the fire failed to ignite or became extinguished since otherwise the closer 57 would reverse the arm. The off-scale contact 91 is connected with a suitable circuit breaker 93 which will shut off the power supply to the main driving motor 10 and actuate a signal device (not shown). Thus the entire plant would be closed down and notice given to the operator of no fire.

Many heating plants employ an automatic switch for cutting off the current supply to the blowers and feed mechanism when the boiler pressure reaches a certain predetermined point. Such a switch does not take into account weather conditions etc., which might require a higher or lower boiler pressure. The present invention can be combined with a switch of this type in order to cause it to allow the boiler to build up a higher pressure in cold weather than in warm weather.

Thus it can be seen that an increasing CO₂ content will cause the CO₂ meter to act through the relay 70 to cause the contacts 43 in the stack thermo-gauge 40 to move to the right so that they cannot be reached by the increasing temperature hand 41. This allows the motor 21 to progressively increase the air supply to the fire until the point is reached when the CO₂ content cannot further increase and an excess of air will be entering the fire. This will cause the CO₂ meter to energize the relay 70 which after a time interval to allow for a CO₂ correction will swing the contacts 43 in the thermogauge 40 against the temperature hand 41 to reverse the air intake control motor 21 to gradually decrease the air supply.

If this does not correct the falling content within another time interval to again return the contacts in the CO₂ meter to normal the relay 87 will start the contacts 62 moving to the left in an endeavor to find a lower CO₂ point for stopping the decrease in air. If this is found, then the air supply again increases, if it is not eventually found, the entire plant will be shut down by the CO₂ meter.

Thus, the system will maintain the stack temperature at the highest point consistent with the highest possible CO₂ content at all times by controlling the air supply responsive to the relation between the flue temperature and CO₂ content.

Such a combination is illustrated in Fig. 4 in which a thermo-responsive device 93 is employed. This device is similar to the thermo-responsive device 23 previously described, that is, it contains the hand 25 responsive to the outside temperature and the hand 24 responsive to the burner temperature, controlled by the conductors 26 and 27 previously described. The device 93, however, contains a contact lever 94 operated from an arcuate rack 95 and worm 96. The device 93 is designed to control one of the usual "mercoid" switches, a typical one of which is indicated at 97.

Such a switch consists of a tilting bar 98, one extremity of which is constantly urged downwardly by a tension spring 99 and constantly urged upwardly by a plunger 100. The plunger 100 is actuated by the steam pressure in the boiler. A glass tube 102 is pivoted on the bar 98 and is provided with a quantity of mercury 103 which closes contact between the electrodes of the main electric feeds 104 to the main motor 10. The amount of pressure required to cause the plunger 100 to tilt the bar 98 so as to throw the mercury away from the electrodes is directly proportional to the amount of tension in the spring 99.

This tension is controlled by a threaded tension screw 105 actuated by a motor 106 which is caused to move forward or in reverse by means of a reversing switch 107. The reversing switch 107 has a constantly energized magnet 108 and an intermittently energized magnet 109. The intermittent magnet 109 is connected through conductors 113 with contacts 111 on the contact

lever 94. The contacts 111 are closed by means of a contact closer 112 mounted on the outside temperature hand 25. The worm 96 is operated by a motor 114 which is controlled by a reversing switch 115. This switch has a constantly energized magnet 116 and intermittently energized magnet 117. The intermittent magnet 117 is in the circuit of the conductors 113 of the magnet 109 of the switch 107.

As the outside temperature falls, the hand 25 will swing to the left until it closes the contacts 111. This will operate the switch 107 by energizing the magnet 109 to cause the motor 106 to increase the tension in the spring 99 so as to require a greater steam pressure in the boiler to operate the mercoid switch to cut off the current supply. At the same time it will operate the switch 115 to cause the motor 114 to swing the arm 94 away from the hand 25 until the contact is broken at 111. If the outside temperature still falls the hand 125 will again make contact and repeat the process, thus the colder the weather the higher will be the steam pressure carried in the heating boiler.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:—

1. Means for controlling the air supply to a burner in consequence of the relation between the temperature of the flue gases and the CO₂ content thereof comprising: a first thermo-gauge connected to operate in consequence of the variations in temperature of said flue gases; a lever adapted to be moved by said gauge; a first contact carried by said lever; a second contact in the path of said first contact, said contacts being connected to control said air supply; and means for varying the position of said second contact so that the latter will be contacted at varying positions depending upon the CO₂ content of said gases.

2. Means for controlling the air supply to a burner in consequence of the relation between the temperature of the flue gases and the CO₂ content thereof comprising: a first thermo-gauge connected to operate in consequence of the variations in temperature of said flue gases; a lever adapted to be moved by said gauge; a first contact carried by said lever; a second contact in the path of said first contact, said contacts being connected to control said air supply; a carbon dioxide mechanism operable by the varying CO₂ content in said gases; a third contact arranged to be closed by said carbon dioxide mechanism; a motor operable by said latter contact, said motor acting to vary the position of said second contact.

3. Means for controlling the air supply to a burner in consequence of the relation between the temperature of the flue gases and the CO₂ content thereof comprising: a first thermo-gauge connected to operate in consequence of the variations in temperature of said flue gases; a lever adapted to be moved by said gauge; a first contact carried by said lever; a second contact in the path of said first contact, said contacts being connected to control said air supply; a carbon dioxide mechanism operable by the varying CO₂ content in said gases; a third contact ar-

5 ranged to be closed by said carbon dioxide mechanism; a motor operable by said latter content, said motor acting to vary the position of said second contact; and means for delaying the impulse from said carbon dioxide mechanism to said motor so that the position of said second contact will not be immediately changed.

4. Means for varying the air supply to a fuel burner comprising: a carbon dioxide gauge 10 mechanism responsive to the CO₂ content of the combustion gases; a first contact member moveable by said gauge mechanism; a second coacting contact member; a moveable support for said second contact so as to vary the point of 15 closing said two contacts; and means for moving said support in consequence of the closing of said first and second contacts and electrical means for varying said air supply in consequence of the closing of said contacts.

20 5. In a fuel burner, means for maintaining the air supply to said burner at a point to produce maximum combustion of the fuel therein comprising: a thermo-responsive device operable by the variations of temperature in the flue gases 25 of said burner; a carbon dioxide responsive device operable by the variations in the CO₂ content of the combustion gases from said burner; contacts in both said responsive devices to be closed at certain positions thereof; means for automatically 30 varying said "certain positions" in each of said devices in consequence of the operation of the other of said devices; and electrical means for varying said air supply in consequence of the closing of the contacts in said thermo-responsive 35 device.

6. Means for automatically controlling combustion in a furnace comprising: a CO₂ meter operable by the chemical contents of the flue gases of said furnace; a first set of contacts 40 closed by said CO₂ meter as the CO₂ content increases; a thermo-responsive device actuated by variations in temperature in said furnace; a second set of contacts in said thermo-responsive device; means for moving said second set of contacts so that they will be closed at varying positions, said means for moving being controlled by said first set of contacts; and electrical means for controlling the air supply to said furnace, said latter means being controlled by said second set of contacts.

7. Means for automatically controlling combustion in a furnace comprising: a CO₂ meter operable by the chemical contents of the flue gases of said furnace; a first set of contacts 55 closed by said CO₂ meter as the CO₂ content increases; a thermo-responsive device actuated by variations in temperature in said furnace; a second set of contacts in said thermo-responsive device; means for moving said second set of contacts so that they will be closed at varying positions, said means for moving being controlled by said first set of contacts; electrical means for controlling the air supply to said furnace, said latter means being controlled by said second set of contacts; and a damped relay in the circuit between said first set of contacts and said means for controlling, so that the action of the latter in one direction will be delayed after said first set of contacts opens.

70 8. Means for automatically controlling combustion in a furnace comprising: a thermo-responsive device operable from temperature changes in said furnace; a contact closer operable by said device; movably mounted contacts positioned to be closed by said closer; a motor

for varying the position of said contacts; a CO₂ meter operable from variations in the CO₂ content of the flue gases of said furnace; other contacts adapted to be closed by said CO₂ meter; and a relay in circuit with said latter contacts and said motor and operating the latter in consequence of operation of said CO₂ meter; and electrical means operable by said first set of contacts 5 for controlling the air supply to said furnace.

9. Means for automatically controlling combustion in a furnace comprising: means for feeding fuel to said furnace; a first movable contact, the moving of which is in consequence of the variations of temperature in said furnace; a second contact arranged to close the circuit with 15 said first contact; means for moving said second contact in consequence of variations in temperature outside said furnace; a reversing relay operable by the opening and closing of said contacts; and electrical means for controlling the 20 action of said relay.

10. Means for controlling the air supply to a burner in consequence of the relation between the temperature of the flue gases of said burner 25 and the CO₂ content thereof, comprising: a first electrical contact; means for moving said first contact in a fixed path in consequence of variations in temperature of said flue gases; a second coacting electrical contact; means for moving 30 said second contact in the same fixed path in consequence of variations in the CO₂ content of said flue gases; and an electrical circuit for controlling the air supply to said burner, said circuit including and being controlled by said two 35 contacts.

11. Means for controlling the air supply to a burner in consequence of the relation between the temperature of the flue gases of said burner and the CO₂ content thereof, comprising: a 40 thermo-responsive device having a pivoted lever swinging in consequence of the variations in temperature of said flue gases; a first contact carried by said lever; a second movably-mounted contact in the path of said first contact; 45 means for varying the contacting position of said second contact in consequence of variations in the CO₂ content of said flue gases; electrical means for controlling the air supply to said burner; and an electric circuit including said 50 two contacts and said electrical means so that said contacts will close said circuit at varying positions of said second contact.

12. Means for controlling the air supply to a burner in consequence of the relation between 55 the temperature of the flue gases of said burner and the CO₂ content thereof, comprising: a first contact; means for moving said first contact in a fixed path in consequence of variations in the temperature of said flue gases; a second 60 coacting contact; means for movably supporting said second contact in the path of said first contact; a CO₂ mechanism; a third contact positioned to be closed by said CO₂ mechanism; a first electric circuit including said third contact; 65 means for moving said second contact in consequence of the closing of said first circuit; and a second circuit for controlling the air supply to said burner, said second circuit including said first and second contacts.

13. Means for controlling the air supply to a burner in consequence of the relation between the temperature of the flue gases of said burner and the CO₂ content thereof, comprising: a first contact; means for moving said first contact 75

- tact in a fixed path in consequence of variations in the temperature of said flue gases; a second coacting contact; means for movably supporting said second contact in the path of said first contact; a CO₂ mechanism; a third contact positioned to be closed by said CO₂ mechanism; a first electric circuit including said third contact; means for moving said second contact in consequence of the closing of said first circuit;
- 10 a second circuit for controlling the air supply to said burner, said second circuit including said first and second contacts; and means for delaying the closing of said first circuit for a predetermined interval.
- 15 14. Means for varying the air supply to a fuel burner comprising; a CO₂ mechanism responsive

to the CO₂ content of the combustion gases of said burner; a first contact movable by said CO₂ mechanism; a second movable contact in the path of said first contact; a movable support for said second contact; a third contact, said movable support being positioned between said first and third contacts; a fourth contact carried by said movable support; means for moving said support in one direction in consequence of the closing of said first and second contacts and in 10 the other direction in consequence of the closing of said third and fourth contacts; and electrical means for varying said air supply in consequence of the closing of said first and second contacts.
